(57) **CLAIM**

The ornamental design for a battery charger handle, as shown and described.

DESCRIPTION

FIG. 1 is a perspective view of a battery charger handle having our design, shown on a battery charger;
FIG. 2 is a perspective view of the battery charger handle of FIG. 1;
FIG. 3 is a top view of the battery charger handle of FIG. 1;
FIG. 4 is a bottom view of the battery charger handle of FIG. 1;
FIG. 5 is a front view of the battery charger handle of FIG. 1;
FIG. 6 is a rear view of the battery charger handle of FIG. 1;
FIG. 7 is a left-side view of the battery charger handle of FIG. 1; and,
FIG. 8 is a right-side view of the battery charger handle of FIG. 1.

The battery charger, shown in broken lines, illustrates an example environment for the claimed battery charger handle and forms no part of the design claimed.
Portions of the battery charger handle shown in dashed lines form no part of the design claimed.
The dash-dot lines in the figures indicate a boundary of the claimed design.
